SAU UND CARL BAMBERG-FRIEDENAU, OF BERLIN-FRIEDENAU, GERMANY.

APPARATUS FOR REGULATING THE GAS MIXTURE IN GAS-FIRED FURNACE
INSTALLATIONS.

Application filed May 22, 1925, Serial No. 32,098, and in Germany May 31, 1924.

This invention relates to a method and an apparatus for regulating the gas mixture in gas-fired furnace installations working with natural suction draft, more particularly in large furnace installations, such as blast furnace boilers, Cowper apparatus and the like.

It has been already proposed to effect a regulation of the gas mixture in furnace installations by determining the pressure in the gas and air pipes for instance by means of baffle plates or the like built into the said pipes and by adjusting the quantity of air or the air pressure by means of a regulating device inserted into the air pipe, in such a manner as to obtain the correct proportion at any time between the quantity of air and the quantity of gas or the air pressure and the gas pressure. These mixture regulators however cannot be used for furnace installations working with natural suction draft, that is to say in which no air supply takes place through an air pipe, more particularly in such furnace installations of specially large size such as blast furnace boilers, Cowper apparatus etc., as a regulation of the air admitted cannot there be carried out.

The present invention obviates this drawback by producing, by means of a regulating device, the same pressure at the gas inlet as at the air inlet. As the air inlet is in communication with the atmospheric air, the arrangement must be such that the gas pressure at the gas inlet shall be always maintained at atmospheric pressure. The predetermined correct ratio between the air and the gas will then be always automatically maintained by the natural draft of the furnace installation, and a regulation of the mixture consumption will then be effected solely through the chimney as the natural suction draft can be regulated by means of the chimney damper.

A construction according to the invention is diagrammatically illustrated in the accompanying drawing in which

Fig. 1 shows the application to a single furnace, whilst

Fig. 2 shows the application to a number of furnaces arranged in parallel.

In Figure 1, *a* is a furnace of the kind in question, for instance a Cowper apparatus.

The air is admitted at atmospheric pressure through the air suction opening *b* opening 55 into the atmospheric air, whilst the gas, for instance blast furnace gas, is supplied through the pipe *c*. In the pipe *c* at the point corresponding to the mouth of the pipe *b*, is provided a baffle plate *d* by means of 60 which the gas pressure at this point, that is at the point at which the gas enters the combustion device, can be measured in a manner well known per se. The pressure acts, also in a well known manner, for instance on a 65 diaphragm *n* or on a piston or on some other servomotor which controls a regulating valve, for instance a throttle valve *e* mounted in the pipe *c*, in such a manner that the gas pressure at the point where the gas is admitted 70 into the furnace installation will be always maintained at atmospheric pressure. On the upper and lower side of the diaphragm *n* two pressure chambers are provided respectively one of which is connected by a pipe *p* 75 with the pipe *c* while the other opens into the atmospheric air. If the pressure in the pipe *c* increases the resulting movement of the diaphragm will close the throttle valve *e* to a greater extent. When the pressure decreases, it will open the valve *e* to a correspondingly greater extent. Within the combustion chamber by the natural draft a pressure is maintained which is less than atmospheric, said pressure being regulable by 80 the usual chimney damper indicated with the reference letter *h*.

As accordingly the same atmospheric pressure will always be obtained at the air inlet and at the gas inlet, the natural suction draft in the combustion installation will draw in air and gas always in the same proportion. The proportion of air and gas in the mixture therefore will always be the same. In order to regulate the total quantity of mixture to be drawn in, it is merely necessary to increase or to reduce the natural draft in the combustion installation, which can be done for instance by a smaller or greater opening of the chimney damper. 90 The proportion between the air inlet opening and the gas inlet opening of course must be fixed beforehand in such a manner that, with equal pressure, the quantity of gas and the quantity of air admitted will form the 95 correct mixture. In installations in which

air instead of being drawn in through a given opening is admitted into the combustion installation, for instance through a grate or other opening which cannot be controlled in its cross-section, it is advisable for the first regulation to provide in the gas pipe, between the baffle plate and the inlet for the gas into the furnace, a regulating damper o or the like which is so adjusted that with equal pressure at the gas and air inlets, the desired mixture will be formed.

10 In place of the baffle plate of course some other device could be used by means of which the pressure at the gas inlet could be regulated.

15 In the case of several combustion installations f, f^1, f^2 connected in parallel, Figure 2, all the installations could be connected to one and the same gas inlet pipe g , and only one pressure regulator h need be inserted into it, which maintains constant the pressure at this point. Into the branch pipes g^1, g^2, g^3 leading from the pipe g to the single furnaces, are then inserted constant resistances for instance baffle plates m, m^1, m^2 which equalize the resistance in the pipe g which is of course different for the furnaces at different distances, in such a manner that the total resistance from the regulator h to the respective combustion chamber f, f^1, f^2 has the same value. All the waste gases could be also discharged into one and the same discharge pipe i in order to enable the suction draft in the same to be uniformly regulated by means of a chimney damper k , while the air is admitted at atmospheric pressure through openings n, n^1, n^2 , opening into the atmospheric air.

20 40 Having now particularly described and ascertained the nature of my said invention and in what manner the same is to be performed, I declare that what I claim is:—

25 45 50 1. A gas-fired furnace comprising a furnace casing having an air suction opening therein in communication with the atmosphere; a pipe for feeding gas to the furnace; means for regulating the pressure in said pipe to maintain the gas adjacent the opening of the pipe into the furnace casing at atmospheric pressure; and means for increasing or decreasing the natural draft in

the furnace casing to thereby regulate the amount of air and gas drawn into the casing.

55

2. A gas-fired furnace comprising a furnace casing having an air suction opening therein in communication with the atmosphere; a pipe for feeding gas to the furnace; adjustable means for regulating the pressure in said pipe to maintain the gas adjacent the opening of the pipe into the furnace casing at atmospheric pressure; a regulating damper in the pipe for regulating the amount of gas to attain a constant 65 proportion of gas and air in the furnace independent of the conditions within the furnace; and means for increasing or decreasing the natural draft in the furnace casing to thereby regulate the amount of air 70 and gas drawn into the casing.

3. A gas-fired furnace comprising a furnace casing having an air suction opening therein in communication with the atmosphere; a pipe for feeding gas to the furnace; 75 adjustable means for regulating the pressure in said pipe to maintain the gas adjacent the opening of the pipe into the furnace casing at atmospheric pressure; means for regulating the air and gas mixture to 80 provide a constant proportion independent of the conditions within the furnace; and means for increasing or decreasing the natural draft in the furnace casing to thereby regulate the amount of air and gas drawn 85 into the casing.

4. A gas-fired furnace comprising a furnace casing having an air suction opening therein in communication with the atmosphere; a pipe for feeding gas to the furnace; 90 adjustable means for regulating the pressure in said pipe to maintain the gas adjacent the opening of the pipe into the furnace casing at atmospheric pressure; means for regulating the air and gas mixture to provide a 95 constant proportion independent of the conditions within the furnace; and a chimney damper for regulating the natural draft in the furnace casing to thereby regulate the amount of air and gas drawn into the cas- 100 ing.

In testimony whereof I have affixed signature.

ERICH PAUL GUIDO WÜNSCH.
